G. CLAUSING

GOLF TEE

Filed March 19, 1927

FIG. 4

INVENTOR
George Clausing
BY Paulmin Paulmin, ATTORNEY

UNITED STATES PATENT OFFICE.

GEORGE CLAUSING, OF PORTSMOUTH, OHIO, ASSIGNOR TO THE VULCAN LAST COMPANY, OF PORTSMOUTH, OHIO, A CORPORATION OF OHIO.

GOLF TEE.

Application filed March 19, 1927. Serial No. 176,811.

My invention relates to golf tees.

It is the object of my invention to provide a golf tee, which may be firmly embedded in the ground in such a manner that the transverse and upward stroke of the club in removing the ball from the tee will not extract the tee from the ground so that the small tee will become lost in the grass.

Accordingly, it is my object to provide a tee which can be screwed into the ground and which will provide spaces between the threads of the screw or the projections on the shaft of the ground attaching means that the soil will enter therebetween and serve to firmly retain the golf tee in position.

Referring to the drawings:

Figure 1 is a side elevation of one form of such a tee;

20 Figure 2 is a top plan view thereof;

Figure 3 is a section on the line 3—3 of Figure 1 looking in the direction of the arrows;

25 Figure 4 is a side elevation of a modification of this screw type.

Referring to the drawings in detail, 1 is a body of any desired configuration, but preferably square, the top of which is cut away as at 2 leaving corner supports 3 having semi-circular inner edges 4 upon which the golf ball rests. The under side of this body is provided with a ground attaching pin or shaft 5 which is provided with a plurality of spaced projections 6 so that there 35 are a plurality of depressions of annular character designated 7 between the raised portions or rings 6. The golf tee of this character when inserted in the ground is provided with means of collecting the soil between the ring 6 so that the removal of the tee is resisted.

40 The tee can be thrust directly down into the ground or it may be twisted into the

ground. The several circular ridges 6 are substantially of the same diameter.

45 Referring to the type shown in Figure 4, 1 is a square head having a golf ball supporting surface 3 while the shaft 5 is tapered to a point 8, but instead of the spaced independent rings 6 I have provided a continuous screw thread 9 with a sharp edge 10 of descending diameter to facilitate the screwing of the tee into the ground, which is particularly effective where there are stones or other obstructions which may resist the 50 penetration of the tee into the ground.

55 It will be understood that I desire to comprehend within my invention such modifications as may be necessary to adapt it to varying conditions and uses.

60 Having thus fully described my invention, what I claim as new and desire to secure by Letters Patent, is:

1. In combination in a golf tee of a head having a ball supporting surface and a shaft 65 having a plurality of independent spaced rings, said rings to be semi-circular in section having valleys therebetween semi-circular in section whereby the tee is securely held in the ground.

70 2. In combination in a golf tee of a head having a ball supporting surface and a shaft having a plurality of independent spaced rings, said rings being semi-circular in section having valleys therebetween semi-circular in section, the end of the shaft being pointed whereby the tee is securely held in the ground.

75 3. In combination in a golf tee of a square head having upwardly projecting semi-circular spaced golf ball supporting edges and a ground attaching shaft having a plurality of separate annular rings whereby the tee is securely held in the ground.

80 In testimony whereof, I affix my signature.
GEORGE CLAUSING.
